United States Patent Office

Des. 201,070
Patented May 11, 1965

201,070

SLIPPER

Winalee Gentry Mitchell, Perrysburg, Ohio
(205 Farnsworth Road, Waterville, Ohio)

Continuation of design application Ser. No. D67,088, Oct.
16, 1961. This application Mar. 13, 1963, Ser. No.
73,997

Term of patent 14 years

(Cl. D7—7)

FIG. 2

FIG. 1

FIG. 3

FIG. 4

FIG. 1 is a perspective view of a slipper showing my new design as it appears in wearing position;

FIG. 2 is a top plan view thereof as it appears in non-wearing position;

FIG. 3 is a bottom plan view thereof; and

FIG. 4 is a side elevational view thereof.

This application is a continuation of my application Serial Number D-67,088, filed October 16, 1961, and now abandoned.

I claim:

The ornamental design for a slipper, substantially as shown and described.
